(57) **CLAIM**

The ornamental design for a footwear upper, as shown and described.

(21) Appl. No.: **29/490,693**

DESCRIPTION

(22) Filed: **May 12, 2014**

FIG. 1 is a top perspective view of a footwear upper showing my new design;

(51) **LOC (10) Cl.** 02-04

FIG. 2 is a lateral elevational view thereof;

(52) **U.S. Cl.**

FIG. 3 is a medial elevational view thereof;

USPC **D2/970**

FIG. 4 is a bottom plan view thereof;

(58) **Field of Classification Search**

FIG. 5 is a top plan view thereof;

CPC A43B 7/08; A43B 5/145; A43B 5/14;
A43B 5/00; A43B 23/00

FIG. 6 is a front elevational view thereof; and,

USPC D2/896, 909-912, 946, 970, 973;

36/83, 109, 45, 50.1, 52, 113, 114, 131

See application file for complete search history.

FIG. 7 is a rear elevational view thereof.

The shaded areas of the toe and heel cap, illustrate a contrasting appearance.

(56) **References Cited**

The even-length broken lines showing on the drawing disclosure within the shaded area represent stitching, a claimed element of the design. The uneven-length broken lines immediately adjacent to the shaded area represent unclaimed boundaries of the design and form no part of the claimed design. The shading lines shown in the drawings represent the three-dimensional contour of the design, and are not intended to indicate surface decoration.
